UNITED STATES PATENT OFFICE.

ALEXANDER TODD IRWIN, OF PITTSBURG, PENNSYLVANIA.

RAILWAY-TRACK LUBRICATOR.

SPECIFICATION forming part of Letters Patent No. 542,828, dated July 16, 1895.

Application filed November 27, 1893. Renewed June 19, 1895. Serial No. 553,382. (No model.)

To all whom it may concern:

Be it known that I, ALEXANDER TODD IRWIN, a citizen of the United States, residing at Pittsburg, in the county of Allegheny and 5 State of Pennsylvania, have invented certain new and useful Improvements in Railway-Track Lubricators; and I do hereby declare the following to be a full, clear, and exact description of the invention, such as will enable 10 others skilled in the art to which it pertains to make and use the same, reference being had to the accompanying drawings, which form a part of this specification.

My invention relates to an improved lubricating device for street and other railway cars; and it consists in a means whereby the rails making sharp curves may be lubricated to prevent wear of the flanges of the wheels, and also to preserve the rails and reduce the 20 number of accidents caused from the cars leaving the track from excessive friction of the parts, together with the certain details of construction and combination of parts, as will be fully described hereinafter.

25 In the accompanying drawings, Figure 1 is a front elevation of a street-railway car provided with my improved device in section. Fig. 2 is a plan view of the truck of the said car, showing the position of my improvement. 30 Fig. 3 is an enlarged sectional elevation of one of the lubricating-boxes, showing a means of bringing the wheel conveying the oil in contact with the flange of the car-wheel.

To provide a street-railway car with my improvement, I attach to the cross-pieces 5 of the truck 4 four oil-boxes 6, each of which is formed in two sections attached at the rear by means of hinges 7 and at the front with spring-clips 8 to hold the two sections together. These boxes 6 are attached to the said cross-pieces 5 by means of integral flanges 18 and bolts and are coupled together in pairs by a shaft 12. Attached to this shaft 12 within each of the boxes 6 is an arm 11, 35 fitted with a loose wheel 10, adapted to be brought against the flanges of the wheels and convey a lubricant thereto. Arranged about each of these shafts 12 is a spiral spring 17, one end of the same being attached to the 40 said shaft and the other to the cross-beam 5 in a manner that will hold the lubricating

wheels or rollers 10 in contact with the flanges of the wheels 2, and keep the same partly immersed in the lubricant contained in the receptacle 9 formed in the bottom of each of 55 the boxes 6, one roller being as shown at the right of Fig. 1 of the drawings. Attached to each of these shafts 12 is a semicircular grooved wheel 13, to each of which is connected a cord or chain 14 passed over suitable pulleys 15 and connected to a part 16, which may represent a lever 16, or to other means of operating the device, which in practice would be arranged within reach of the 60 trainman.

In operation the lubricating-rollers 10 when at rest are partly immersed in the oil in the bottom of the boxes 6, and when it is desired to lubricate the track when passing about sharp curves the shaft 16 is operated to bring 70 the rollers 10 in contact with the flanges of the wheels 2, which will convey the fluid to the track 3, and when the pressure on the said shaft 16 is removed the rollers will be returned to their normal position free from 75 the said flanges by the action of the spiral springs 17.

By means of this device the track may be lubricated while the car is in motion.

Having thus described my invention, what 80 I claim, and desire to secure by Letters Patent, is—

The described device for lubricating the rails of a railway-track, consisting of lubricant boxes, the lubricant-applying rollers arranged in said boxes, shafts bearing said rollers, a segmental or semi-circular wheel fixed to each of said shafts, means connected to said segmental wheels for throwing said lubricant-applying rollers into contact with 85 the flanges of the car wheels, and springs applied to said shafts and adapted to return the rollers to the lubricant boxes and to retain them immersed in the lubricant therein, substantially as set forth.

In testimony that I claim the foregoing I hereunto affix my signature this 5th day of September, A. D. 1893.

ALEXANDER TODD IRWIN. [L. S.]

In presence of—

ALBERT J. WALKER,
M. E. HARRISON.
